DESIGN FOR A SLICER

Robert W. Linenfelser, Monroe, Mich.

Application May 17, 1941, Serial No. 100,999
In Canada April 10, 1941

Term of patent 14 years

To all whom it may concern:

Be it known that I, Robert W. Linenfelser, a citizen of the United States, residing at Monroe, in the county of Monroe and State of Michigan, have invented a new, original, and ornamental Design for a Slicer, of which the following is a specification, reference being had to the accompanying drawing, forming part thereof.

In the drawing:

Fig. 1 is a perspective view of a slicer, showing my design; and

Fig. 2 is a vertical mid-sectional view thereof.

The dominant feature of my design resides in the platform portion of the slicer.

I claim:

The ornamental design for a slicer, as shown and described.

ROBERT W. LINENFELSER.
